HARRISON L. STALEY AND FRANK J. ROCK, OF RICHMOND, VIRGINIA.

GASKET-SEAT-CLEANING TOOL.

Application filed April 6, 1920. Serial No. 371,649.

To all whom it may concern:

Be it known that we, HARRISON L. STALEY and FRANK J. ROCK, citizens of the United States of America, and residents, respectively, of Richmond, county of Henrico, and State of Virginia, have invented certain new and useful Improvements in Gasket-Seat-Cleaning Tools, of which the following is a full and clear specification.

10 In water-tube boilers, it is customary to provide the boiler-head with a series of holes in alinement with the water-tubes for the purpose of inserting tube-cleaning devices. These holes are closed while the boiler is in use by covers which are clamped against the inner face of the boiler-head, a gasket being clamped between the cover-plate and the boiler-head to ensure a gas-tight joint. When these cover-plates are removed to permit access to the water-tubes, the gasket has so deteriorated that parts of it stick to the gasket-seat formed on the boiler-shell, and these rough parts of the gasket must be thoroughly scraped off before a new gasket 20 can be put into place. It is the object of the present invention to provide a simple rotary tool for cutting away the débris of the gasket, whereby this work may be done with great expedition and thoroughness, as more 25 fully hereinafter set forth.

In the drawings—

Fig. 1 is a side elevation of our device showing it in the act of being put in position for use;

35 Fig. 2 is an end view of the cutter-head with the cover-plate removed;

Fig. 3 is a longitudinal section through the cutter-head.

Referring to the drawings annexed by 40 reference-characters, *a* designates a shaft which carries at one end a cylindrical cutter-head *b* which has a limited rotation upon said shaft *a*, the other (outer) end of the shaft being provided with means for conveniently rotating the shaft, a hand-crank *c* being shown in the present instance. The cutter-head *b* is of a size to freely fit into the usual hand-hole in the boiler-shell *d*.

The forward end of the shaft *a* terminates 50 within the cutter-head and has affixed to it a disk *e*, this disk being covered by a head-disk *f* fastened to the forward face of the cutter-head by bolts *g*, said disk *f* being recessed on its inner face to form a circular chamber for the disk *e*. This disk is pro-

vided with a plurality of radial slots *h*, three being shown in the present instance, the device shown being adapted to carry three cutters *i*. These cutters are in the form of a bar substantially rectangular in cross-section and arranged tangentially on the cutter-head, the inclination being in the direction of normal rotation, which is shown by the arrow in Fig. 2. Each cutter is slidably mounted in a tangential groove in the head *b* and is provided with a pin *j* which enters one of the slots *h*, so that the rotation of the disk will either project the cutters into operative position, as shown in dotted lines in Figs. 1 and 2, or retract them to inoperative position, shown in full lines in said figures.

The cutter-head is provided at its outer end with an annular flange *k* which, when the cutter-head is inserted to its fullest extent in the hole in the boiler plate, will bear against the outer face of the boiler-plate. Slidably mounted on the shaft *a* is a cross-bar *l* which is provided at each end with a forwardly-extending foot *l'*, this bar with its feet forming a sort of yoke which straddles the cutter-head, the forward ends of the feet being in position to bear against the outer face of the boiler-head when the cutter-head is inserted in the cleaning-hole. This cross-head is normally pressed toward the cutter-head by a coil-spring *m* surrounding the shaft, the tension of this spring being regulated by means of an abutment-collar *n* adjustably fastened to the shaft *a* by a set-screw *o*.

As shown in Fig. 1, to apply the device it is simply necessary to insert the cutter-head into the hole in the boiler-head and press upon the outer end of the shaft *a* to compress the spring *m* sufficiently to bring the flange *k* against the front face of the boiler-head; then, by giving the shaft *a* a partial turn, in the direction of the arrow shown in Fig. 2, by means of its hand-crank, the disk *e* will be rotated sufficiently 95 to project the cutters into cutting position, that is, far enough outwardly to encompass the gasket-seat formed on the inner face of the boiler-shell. During this movement of the disk *e* and the connected cutters, the body *b* of the cutter-head is held against rotation by friction of the flange *k* against the boiler-shell, but, as soon as the cutters are fully projected, it will be obvious that the arrangement of the pins and slots is 100 105 110

such that the disk will be locked against further independent rotation and that, therefore, the disk and the body *b* will rotate together. This stoppage of the disk is caused by the pins *j* coming into contact with the outer wall of the recess in which the disk *e* is housed. After the cutters are thus projected, it will be seen that the device will be locked in the hole in the boiler-
sheet, in that it cannot be withdrawn from the hole until the cutters are retracted by an opposite rotation of the shaft *a*. After the cutter-head is thus locked in the hole, pressure may be relieved from the outer end of the shaft *a* and thus permit the spring to force the shaft *a* outwardly far enough to bring the cutting edges of the cutters against the gasket-seat, as shown in dotted lines in Fig. 1. Then the tool is ready for operation, the operation being carried out by simply holding the tool up against the boiler-head with one hand while rotating the shaft *a* with the other hand. During this operation, it will be observed that the spring holds the cutters resiliently against the work, the degree of pressure being determined by the position of the collar *n*. In actual tests, it has been found that the gasket-seat may be thoroughly cleaned of the gasket débris by a few turns of the cutter-head. The resilient pressure maintained on the cutters is important, of course, in that it enables the cutters to yield slightly in repeatedly passing over the larger pieces of the gasket débris until they are entirely cut out and the cutters are all working smoothly on the bottom of the gasket-seat.

It will be observed that the tangential arrangement of the cutter-bars is advantageous in that it ensures the débris being removed by a sort of draw cut. This arrangement of the cutters is advantageous also for the reason that it prevents the cutters being withdrawn by the independent rotation of the disk in certain operations where the parts of the gasket stick so hard to the seat that it facilitates their removal to be able to oscillate the tool instead of rotating it continuously in a forward direction; that is to say, when particularly obstinate pieces of gasket are encountered, they can be better removed by wiggling or oscillating the tool back and forth, and the cutters are prevented from being retracted by pressure against the gasket-seat caused by the spring *m*. In other words, while the cutters may be retracted by reverse rotation of the disk *e*, when the cutter-head is pressed inwardly far enough to relieve the cutters from pressure against the seat, the cutters will not be retracted by such reverse rotation of the shaft while they are in forcible engagement with the gasket-seat; this, as stated, enables the cutter-head to be os-

cillated whenever it is desirable to do so in working on a particularly obstinate piece of gasket. This ability to oscillate the tool (i. e., ratchet fashion) is further advantageous for the reason that in some locations there is not room enough to completely rotate the crank-handle.

The nature and scope of the invention having been thus indicated and its preferred embodiment having been specifically described, what is claimed as new is:

1. In a tool of the class set forth, a support, a cutter-head carried by a shaft and adapted to be inserted in a hole in the boiler-plate and carrying cutters normally in inoperative position adapted to be projected beyond the circumference of the cutter-head so as to work against the gasket-seat on the inner face of the boiler-plate, and means whereby the shaft may be rotated independently of the cutter-head and the cutters projected after the cutter-head is inserted, means being provided for clamping the tool in the hand-hole while in operation. 90

2. In a tool of the class set forth, a support, a shaft provided at its outer end with means for rotating it and at its inner end with a cutter-head adapted to pass into the cleaning-hole in the boiler-sheet, said cutter-head being provided with cutters adapted to be retracted to inoperative position for insertion into the cleaning hole and to be projected beyond the circumference of the cutter-head after it is inserted so as to engage the gasket-seat on the inner face of the boiler-sheet, resilient means being provided for pulling the cutting-edges of the tool against the gasket-seat while in operation. 95

3. In a tool of the class set forth, a shaft and means at one end for rotating it, a cutter-head at the other end of the shaft adapted to be inserted in the cleaning-hole, said cutter-head being provided with cutters adapted to be retracted to inoperative position for insertion into the cleaning-hole and to be projected beyond the circumference of the cutter-body so as to engage the gasket-seat on the inner face of the boiler-sheet, and resilient means for causing said cutters to resiliently engage the gasket-seat during rotation of the cutter-head. 110

4. In a tool of the class set forth, a support, a shaft, a cutter-head mounted on the inner end of the shaft and having a limited rotation thereon and carrying cutters adapted to be projected outwardly beyond the cutter-head body, and means whereby rotation of the shaft independently of the cutter-head will project the cutters or retract them, for the purpose set forth, means being provided for not only clamping the tool in position on the boiler wall but also 125

for holding the cutter-head against rotation when the shaft is initially rotated to project the tools to working position.

5. In a tool of the class set forth, a shaft support, a shaft having a cutter-head mounted on its inner end in such manner as to have a limited rotation thereon independently of the cutter-head, tangentially-arranged cutters carried by said head, and means operated by said shaft for projecting as well as retracting said cutters, for the purpose set forth, means being provided for holding the cutter-head against rotation while the cutters are being projected to working position.

6. In a tool of the class set forth, a shaft carrying at one end a cutter-head and means whereby it has a limited independent rotation on the shaft, a disk affixed to the shaft, cutters carried by the head and means whereby independent rotation of the shaft will cause said disk to project the cutters into working position, and means whereby the cutters when projected to working position will be held to their work.

7. In a tool of the class set forth, a shaft, a cutter-head rotatably mounted on the inner end thereof and provided with a flange at its outer end and with a series of cutters adapted to be projected beyond the circumference of the cutter-head, resilient means carried by the shaft for pressing against the outer face of the boiler-sheet, said shaft being provided with means whereby it may be rotated, and means also being provided whereby the initial rotation of the shaft in one direction causes the cutters to be projected to working position and initial rotation in the other direction causes the cutters to be retracted to non-working position.

8. In a tool of the class set forth, a shaft provided with means for rotating it at its outer end and with a rotatable head at its inner end, said head being provided with a flange at its outer end and with retractable and projectable cutters at a point beyond the flange, means operated by the initial rotation of the shaft in one direction for projecting the cutters and by the initial operation of the shaft in the other direction for retracting them, a yoke slidably mounted on the shaft and adapted to straddle the cutter-head and bear upon the outer face of the boiler-sheet at points outside of the hand hole, and spring-means on the shaft for normally pressing said yoke toward the cutter-head.

9. In a tool of the class set forth, a shaft provided at one end with means for rotating it and at its other end with an independently-rotatable cutter-head, a disk affixed to the inner end of the shaft and housed within the cutter-head, said disk being provided with radial slots, and slid-

able tangentially-arranged cutters in the head, each being provided with a pin adapted to engage with one of said slots, means being provided for holding the cutter-head against rotation while the cutters are being projected to working position.

10. In a tool of the class set forth, a shaft, a head adapted to pass into the hand-hole and carrying a series of cutters adapted to slide inwardly and outwardly, means being provided whereby said head has only limited rotatability on said shaft, means affixed to the shaft for projecting the cutters to working position and withdrawing them to non-working position, said head being provided with means whereby it may be temporarily held against rotation by engagement with the boiler-sheet, and a spring-pressed means mounted on the shaft for engaging the adjacent side of the boiler-sheet, this spring-pressed means tending to withdraw the head from the hand-hole.

11. In a tool of the class set forth, a support, a shaft carrying a cutter-head adapted to pass into the hand-hole, sliding cutters carried by the head, and means whereby these cutters may be withdrawn to a non-operative position to permit the cutter-head to pass into the hand-hole whereby the cutters may be projected into operative position to engage the inner face of the boiler-wall, means being provided for holding the cutter-head against rotation while the cutters are being projected to working position.

12. In a tool of the class set forth, a support, a shaft mounted in said support and carrying a tool-head at its inner end adapted to pass into the hand-hole, said shaft and said head having limited independent rotatability, cutters carried by the head and adapted to be withdrawn to non-operative position to permit the head to be passed into the hand-hole and to be projected to operative position to engage the gasket-seat on the inner face of the boiler-wall, and means whereby these movements of the cutters may be accomplished by relative rotation of the shaft and tool-head, means being provided for clamping the tool in position on the boiler-head with the cutting-edges in position for operation.

13. In an appliance of the class set forth, a support, a shaft mounted in said support and carrying a tool-head at its inner end adapted to pass into the hand-hole, said shaft and said head having limited independent rotatability, tools carried by the head and adapted to be withdrawn to non-operative position to permit the head to be passed into the hand-hole and to be projected to operative position to engage the gasket-seat on the inner face of the boiler-wall, and means whereby these movements of the tools may be accomplished by relative

rotation of the shaft and tool-head, said tool-head being provided with means whereby the head may be pressed into frictional engagement with the boiler-wall while the tools are being projected into working position.

14. In an appliance of the class set forth, a shaft carrying at its inner end a tool-head adapted to be passed into the hand-hole and having a limited rotatability on the shaft, means whereby the relative rotation of the shaft and the head will project the tools into working position, a supporting member, and resilient means for pressing the head against the boiler-wall when the tool-head is pushed into the hand-hole, said tool-head being provided with means for engaging the boiler-wall to thus hold the tool-head against rotation while the shaft

is being rotated independently of the tool-head to project the tools to working position.

15. In a tool for the purpose set forth, a rotatable shaft, a cutter-head freely mounted on said shaft and having grooves therein, cutters slidably movable in said grooves, means connected to said shaft and engaging said cutters so as to slidably move the same on the rotation of said shaft, and means for holding said cutter-head stationary temporarily when said shaft is rotated.

In testimony whereof we hereunto affix our signatures this 30th day of March, 1920.
